Patented May 11, 1920.

UNITED STATES PATENT OFFICE.

EUGENE L. BAKER, OF TAUNTON, MASSACHUSETTS.

MOLDING DEVICE.

1,339,642.

Specification of Letters Patent. Patented May 11, 1920.

Application filed February 3, 1920. Serial No. 356,041.

To all whom it may concern:

Be it known that I, EUGENE L. BAKER, a citizen of the United States, residing at Taunton, in the county of Bristol and State of Massachusetts, have invented a new and useful Molding Device, of which the following is a specification.

The structure forming the subject matter of this application is a molding device, and 10 the invention aims to provide novel means whereby the sand-carrying frames may be swung over onto the patterns, be swung off the patterns, and be swung together, thereby to complete the mold without lifting the 15 sand-carrying frames bodily, either with respect to the pattern frame or with respect to each other.

It is within the province of the disclosure to improve generally and to enhance the 20 utility of devices of that type to which the invention appertains.

In the accompanying drawings:—

Figure 1 shows in plan, a device constructed in accordance with the invention; 25 Fig. 2 is a side elevation, showing the structure as it will appear after one of the sand frames has been swung over on top of the other sand frame; Fig. 3 is a section taken approximately on the line 3—3 of Fig. 1 and 30 showing one of the hinges; Fig. 4 is a section taken approximately on the line 4—4 of Fig. 1, and showing another of the hinges; and Fig. 5 is a fragmental plan disclosing a modification.

In carrying out the invention there is provided a main or pattern frame 1, within 35 which may be located plates 2 held in place by set screws 3, the plates 2 carrying patterns 4. The patterns 4 of one plate correspond to one-half of the object to be cast, whereas the patterns of the other plate correspond to the other half of the object to be 40 cast. The patterns may be held on the frame 1 in any desired way, although the plates 2 and the set screws 3 are an expedient means to this end.

The invention comprises a pair of sand frames 5 and 6 disposed end to end and located along one side of the pattern frame 1. 50 The constituent parts of the sand frames 5 and 6 may be made to open, the said parts of the frames being connected by hinges 7 and by hooks 8 adapted to coöperate with keepers 9.

55 The sand frame 5 is connected with the

pattern frame 1 by separable first hinges, which may be variously constructed. These hinges may embody pins 10, carried by ears 11 on the pattern frame 1, and hooks 12 on the frame 5. The first hinges which connect 60 the frame 6 with the frame 1 may be in the form of ears 14 on the respective frames, the ears being united by pivot pins 15. The ends of the frames 5 and 6 are connected by second hinges 16 formed, if desired, like the 65 hinges 10—12. The frames 5 and 6 and the pattern plates 2 may be provided with inter-engaging elements 17, in the form of pins and openings, adapted to prevent relative lateral movement between the frames 5 and 70 6 on the one hand, and the frame 1 on the other hand, when the frames 5 and 6 are swung over on top of the frame 1 as herein-after described.

In practical operation, the frames 5 and 75 6 are swung together, on the hinges 10—12 and 15—14, on top of the frame 1 and the pattern plates 2. The sand is then rammed into the frames 5 and 6. The frames 5 and 6 then are swung off the frame 1 on a pallet 80 30, shown in Fig. 2. The frame 5 is swung on the hinges 16 on top of the frame 6. The frames 5 and 6 then are opened at the hinges 7, and the complete mold, cleared from the frames 5 and 6, is carried away to 85 the point of casting. It is to be observed that since the hinges which connect the frame 5 with the frame 1 are of the form shown in Fig. 3, the frame 5 will be disconnected automatically from the frame 1 90 when the frame 5 is swung over on top of the frame 6.

At times, it may be desirable to effect the casting operation while the sand is inclosed within the frames. Then, referring to Fig. 95 5, the frames, such as the frame 6^a are fashioned solid, the hinges 7 being omitted. After one of the sand frames has been folded over on top of the sand frame 6^a in Fig. 5, the frame 6^a is disconnected from the 100 pattern frame 1^a. To facilitate this operation, the hinges 25 of Fig. 5, corresponding to the hinges 14—16 of Fig. 1, are constructed like the hinges 10—12 of Fig. 3.

The various hinges hereinbefore alluded 105 to may be constructed in a variety of ways, the object in view being to permit, first, the frames 5 and 6 to be swung over on top of the frame 1 and, second the frames 5 and 6 have been swung off the frame 1 to permit 110

the frame 5 to disengage itself automatically from the frame 1 and to permit the frame 5 to be swung over on top of the frame 6.

The construction of the device is such that 5 the work incident to handling the various frames is cut down appreciably. Under the old procedure, the frames 5—6 were first lifted bodily upon the frame 1, then lifted bodily off the frame 1 and finally lifted one 10 on top of the other. The structure shown in the drawing, therefore, does away with three lifting operations calling for the expenditure of considerable strength.

Having thus described the invention, 15 what is claimed is:—

In a device of the class described, a pattern frame; a pair of sand frames; first hinges uniting the sand frames with the

pattern frames whereby both sand frames may be swung on top of the pattern frame 20 and be swung off the pattern frame, one of the first hinges comprising separable parts whereby one sand frame may be swung on top of the other sand frame after both sand frames have been swung off the pattern 25 frame; and a second hinge connecting the sand frames and permitting one sand frame to be swung on top of the other sand frame as aforesaid.

In testimony that I claim the foregoing as 30 my own, I have hereto affixed my signature in the presence of two witnesses.

EUGENE L. BAKER.
